UNITED STATES PATENT OFFICE.

ZEBULON DAVIS, OF CANTON, OHIO.

VAPOR-BURNER.

SPECIFICATION forming part of Letters Patent No. 258,385, dated May 23, 1882.

Application filed February 18, 1882. (No model.)

To all whom it may concern:

Be it known that I, ZEBULON DAVIS, of Canton, in the county of Stark and State of Ohio, have invented certain new and useful Improvements in Vapor-Burners; and I do hereby declare the following to be a full, clear, and exact description of the invention, such as will enable others skilled in the art to which it pertains to make and use it, reference being had to the accompanying drawings, which form part of this specification.

My invention relates to an improvement in vapor-burners; and it consists in pivoting to the under side of the burner an induction-tube, which is connected, by means of a rod which passes up through the burner, with the cap of the burner, so that when the induction-tube is moved partially around by means of its handle the cap will be moved back from over the top of the burner. The object of this part of my invention is to connect the induction-tube and the removable top of the burner together by means of a rod which passes up directly through the burner, and thus protect the rod from the heat of the flame to which it is exposed when the rod passes up upon the outside.

The second part of my invention consists in forming an inclined plane or deflector upon one side of the induction-tube, so that when the tube is turned to one side the deflector will guide a portion of the flame or vapor directly into the bottom of the burner. The object of this part of my invention is to form a deflector upon one side of the induction-tube, so that when the tube is swung around sufficiently far to one side the deflector will guide a portion of the flame directly into the bottom of the burner, while enough of the flame will be diverted against the fluid-pipes to maintain the heat of vaporization, and thus keep the burner ready for instant use.

Figure 1 is a vertical section of my invention. Fig. 2 is a side elevation of the same. Fig. 3 is an inverted view of the burner, taken on the line *a b*, Fig. 1. Fig. 4 is a detail view of the induction-tube, connecting-rod, cap, and lever. Fig. 5 is an inverted view of the burner, showing the deflector moved to one side, so as to only slightly expose the opening into the burner. Fig. 6 is a side elevation of the cap,

the connecting-rod, induction-tube, and deflector, taken at right angles to Fig. 4.

A represents the inlet pipe or tube, through which the fluid is passed toward the burner, and upon which the burner B is placed. From the pipe A the fluid passes through the small pipe C, which is provided with the regulating-screw D in the usual manner, which screw has the lighting-cup attached to it.

Pivoted upon the bottom of the burner is the induction-tube E, which has the inclined plane F formed upon one side for the purpose of forming a deflector. The pivotal rod G, upon which this tube is fastened, passes up directly through the burner, and is connected to the top of the burner at its upper end in such a manner that when the induction-tube is moved the top or cap V of the burner will be moved at the same time. This pivotal rod is passed up through the burner for the purpose of protecting it from the heat of the flame to which it is subjected when placed outside of the burner. This inlet-tube and cap of the burner are connected together, so that when either one is moved the other will be moved at the same time; or, if so desired, the induction-tube and the cap may be hinged separately and each one provided with a handle or other means for moving it, instead of being connected together, as shown; or the cap or top of the burner may be formed solidly with the reservoir, and the induction-pipe alone may be moved for the purpose of deflecting all of the vapor and flame against the fluid-conducting pipe for the purpose of maintaining the heat of vaporization and keeping the burner always ready for instant use.

The object in making the cap or cover of the burner movable is to move it to one side, so that the flame is guided up through the burner and burns through the opening which is made by moving the cap, instead of burning through the small openings made in the side of the burner in the usual manner. Where the cap is thus made movable a smaller heating-flame can be maintained with safety in the burner than can be done where the cap is formed as a part of the burner, and the flame must be burned through the small holes in its sides at the same time that the flame can be brought up nearer to the object which is to be heated, and thus

used more directly and advantageously. When the cap is cast solidly as a part of the burner the induction-tube will be made movable and have the deflector formed upon its side sufficiently flaring or large so that when the tube is moved laterally upon its pivot the deflector will cover the opening into the bottom of the burner, and thus prevent the passage of any of the vapor into the burner, and hence cause it all to be burned upon the outside, where it will maintain the heat of vaporization and keep the burner ready for instant use. Where the cap is not made movable the vapor is not allowed to enter the burner when a full flame is not wanted, for the reason that there will not be sufficient gas to support a positive and safe flame, and hence will cause an unpleasant smell to be emitted from the burner by the unconsumed vapor.

Having thus described my invention, I claim—

1. A vapor-burner having an induction-tube pivoted to its under side, in combination with a connecting-rod and movable cap, the tube

and cap being connected directly and rigidly together, substantially as shown.

2. In a vapor-burner, the combination of a pivoted induction-tube, a movable cap or top, and a connecting-rod which passes up through the burner, whereby the cap and induction-tube are made to move together, substantially as described.

3. The combination of a vapor-burner with a pivoted induction-tube, the induction-tube having a deflecting-surface, F, formed upon its side, substantially as set forth.

4. The combination of the vapor-burner with an induction-tube having a deflector formed upon its side, and a movable cap, whereby an auxiliary heating-flame may be maintained at the top of the burner, substantially as specified.

In testimony whereof I affix my signature in presence of two witnesses.

ZEBULON DAVIS.
